UNITED STATES PATENT OFFICE

2,417,598

WRENCH FOR SHIELDED SPARK PLUGS

John Paul Jones, Brownsville, Tex.

Application September 23, 1944, Serial No. 555,561

5 Claims. (Cl. 81—125)

1

This invention relates to socket wrenches for shielded spark plugs of the type used in airplane engines and, among other objects, aims to provide a greatly improved socket member adapted to be positively engaged with and gripped on a non-circular head or nut of a shielded spark plug by means of a screw threaded nut engaging the shield member or shell to prevent damage to the plug when it is tightened or removed.

Another aim is to provide a simplified form of cylindrical socket member and wrench handles adapted to engage the holding nut and the socket member. The main idea is to provide an improved socket wrench of this type which greatly facilitates the insertion and removal of shielded spark plugs used in large airplane engines.

Other aims and advantages of the invention will appear in the specification when considered in connection with the accompanying drawings, wherein:

Fig. 1 is a sectional view, partly in elevation, showing one form of the wrench applied to a shielded spark plug;

Fig. 2 is a vertical sectional view taken on the line 2—2 of Fig. 1, showing parts of the socket member;

Fig. 3 is a sectional view taken on the line 3—3 of Fig. 1.

Fig. 4 is an upper end view of the socket shown in Fig. 2;

Fig. 5 is a sectional view taken on the line 5—5 of Fig. 2;

Fig. 6 is a longitudinal view, partly in section, of a handle for manipulating the socket member; and

Fig. 7 is a fragmentary view, similar to Fig. 4, showing the handle applied to the upper end of a socket member.

Referring more particularly to the drawing, the special type of socket wrench there shown, is designed to be used on a shielded spark plug 10, wherein an insulating shield is protected by a shield member or tubular shell 11 having screw threads 12 at its upper end to which a conductor fitting or elbow (not shown) is adapted to be engaged. "Champion" spark plugs are commonly used in airplane engines. They have a narrow nut section 13 which has to be engaged by a socket wrench to remove and replace them. Experience has demonstrated that ordinary socket wrenches soon damage the hexagon or non-circular heads to such an extent that the spark plugs have to be discarded. This is especially true when the plugs become frozen in an engine and require considerable turning effort to

remove them. In accordance with this invention, the screw threads in the shield member or shell are utilized for the purpose of positively gripping and holding a socket member on the plug, thereby preventing accidental disengagement from the plug and consequent damage to the non-circular head.

Referring to Figs. 1 and 2, the socket wrench portion is shown as comprising an elongated tube 14 having a non-circular socket 15 at its lower end and presenting an internal sleeve 16 telescoped within the tube. The lower socket member is preferably, although not necessarily, formed of a separate piece, and welded in the lower end of the tube, so that it presents a shoulder 17 on the inside of the tube at a height substantially equal to the height of the plain shank 11 of the protecting sleeve member or shell 11. The tube is shown as having an elongated sight opening 18 on one side and a tubular, floating nut 19 is slipped into the tube so that it can rotate with respect to the tube. It is shown as having a screw threaded, internal thimble 20 adapted to be screwed on the screw threaded portion 12 of the shell or sleeve member 11. Its lower end engages the shoulder 17 to clamp the socket 15 on the nut portion 13 of the plug, with the lower end of the socket engaging the usual flange 21 of the plug below the nut portion.

The floating nut is shown as having a squared socket portion 22 at its upper end adapted to be engaged by the shank of a small wrench handle 23, inserted in the upper end of the tube 14, as shown in Fig. 1. When the floating nut is screwed home on the screw threads 12 of the sleeve portion 11, the spark plug is positively engaged by the socket and the wrench handle 23 is then removed.

The upper end of the sleeve 14 has a square socket member 24 adapted to be engaged by an ordinary socket wrench handle. In this instance, there is shown a handle 25 having a square shank 26 at its upper end and a pivoted shank 27 at its lower end adapted to be turned at a right angle, as shown in Fig. 7, to engage the socket 24 and afford ample leverage to turn the wrench socket. Of course, other male and/or female handles can be employed to extend the effective length of the socket wrench in case the spark plugs are relatively inaccessible. For example, a second plug socket member 14 can be employed to engage the pivoted shank 27, when turned at a right angle, while the straight shank 26 is engaged in the upper socket 24. Moreover, the pivoted shank 27, when in the position shown in Fig. 6,

can be engaged in the socket 24 and an ordinary straight handle (not shown) inserted in an opening 28 near the upper end of the handle. The handle 25 is shown as being knurled to facilitate gripping. Likewise, the barrel or outer surface of the tube 14 may be knurled to facilitate turning by hand when the spark plug is loose in its screw threaded opening.

From the foregoing description, it will be seen that the wrench is designed to protect spark plugs and prevent damage to the non-circular heads. Also, it prevents accidental disengagement of the spark plugs from the sockets when the spark plugs are removed. Experience has demonstrated that a wrench of this type is greatly in demand. It has served the purpose of removing spark plugs many times without any noticeable damage. In fact, it is contemplated that it will displace other socket wrenches for removing and replacing shielded spark plugs.

Obviously, the invention is not restricted to the particular embodiment herein shown and described.

Having thus described the invention what is claimed is:

1. A spark plug wrench of the character described comprising in combination, a tubular member having a plug engaging socket at its lower end; a floating nut rotatably mounted within the tube adapted to engage a screw threaded shield member on the upper end of the spark plug; a stop shoulder for the nut in the tube, so arranged that the nut will clamp the socket on the spark plug; a removable wrench handle for the floating nut adapted to be inserted in the tube; a wrench socket in the upper end of the tube; and a handle having a shank adapted to engage said upper socket.

2. A socket wrench for spark plugs having a screw threaded shield member comprising an elongated tube having a wrench socket to engage the spark plug; a shoulder within the tube around the shank of the shield member; a nut confined to rotate and slide up and down in the tube and adapted to be screwed on the shield member into engagement with said shoulder to clamp the wrench socket on the spark plug; a wrench handle removably engageable with the floating nut adapted to be inserted in and removed from the tube; and a non-circular wrench socket in the upper end of the tube adapted to be engaged by the shank of a wrench handle.

3. A spark plug wrench of the character described comprising in combination, a tubular

member having a plug engaging socket at its lower end; a shoulder portion above the spark plug engaging socket within the tube; a floating nut rotatably mounted within the tube adapted to be

5 screwed on a screw threaded shield member on the upper end of the spark plug and into engagement with said shoulder to clamp the socket on the spark plug; a removable wrench handle for the floating nut adapted to be inserted in the tube; a wrench socket in the upper end of the tube; and a handle having a shank adapted to engage said upper socket.

4. A socket wrench for spark plugs having a screw threaded shield member, comprising in combination, an elongated tube having a wrench socket to engage and rest on the head of a spark plug; a shoulder within the tube around the shank of the shield member; a nut confined to rotate and slide up and down in the tube and adapted to be screwed on the shield member into engagement with the shoulder to clamp the wrench socket on the spark plug; a wrench handle removably engageable with the floating nut adapted to be inserted in and removed from the tube; and a non-circular wrench socket within the upper end of the tube and confining the floating nut therein.

5. A wrench for spark plugs having a screw threaded shield member, comprising a tubular section having a plug socket in one end to rest on the head of a spark plug; an annular shoulder above the plug socket; a floating nut confined in the tubular section adapted to be screwed on the shield member into engagement with said shoulder to clamp the plug in the socket; a nut operating member insertable through the other end of the tubular member and removably engageable with said nut; and handle receiving means in said other end of the tubular member.

JOHN PAUL JONES.
